J. B. BURDETT

PRESSURE REGULATOR

Filed April 19, 1923

UNITED STATES PATENT OFFICE.

JOHN B. BURDETT, OF HIGHLAND PARK, ILLINOIS.

PRESSURE REGULATOR.

Application filed April 19, 1923. Serial No. 633,243.

To all whom it may concern:

Be it known that I, JOHN B. BURDETT, a citizen of the United States, residing at Highland Park, in the county of Lake and State of Illinois, have invented certain new and useful Improvements in Pressure Regulators, of which the following is a specification.

The object of this invention is to produce a simple, practical pressure regulator which has its indicators contained in the same structure, and the dials of the indicator mounted in suitable relation to the adjusting handle.

Another object of the invention is to provide a simplified valve and valve-control mechanism in a pressure chamber, which can be readily removed for inspection and repair through the opening covered by the diaphragm.

Another object is to prevent the operator from injuring the diaphragm by adjusting the screw too far in.

Another object is to simplify the assembling of the indicator into the device and to do away with all outside connections.

Referring to the accompanying drawings: Fig. 1 is a cross section of a pressure regulator embodying my invention.

Fig. 2 is a section on line 2—2 of Fig. 1.

Fig. 3 is a section on line 3—3 of Fig. 1.

The housing 1 of the device is cylindrical in form and has a transverse partition 2 dividing it into a pressure chamber 3 and a compartment 4. The chamber 3 is covered by a diaphragm 5 which is held in place over the end of the housing 1 by the cover or bell housing 6, which is threaded or otherwise removably secured to the housing 1.

The inlet passage 7 is formed in the side wall of the chamber 3 and is tapped externally to receive the fitting 8 by which the whole device is secured to the gas-storage tank and connected to the gas under high pressure which is contained in the tank. The inlet nozzle 9 is threaded into the inlet passage 7 and extends parallel to the diaphragm 5. The inner end of the nozzle 9 is covered by a screen 10 which is secured in the end of the nozzle. The valve seat 11 is formed around the opening in the nozzle, and a tubular guide portion 12 is formed concentric with the valve-seat. A disk-shaped valve 13 co-operates with the valve-seat 11 and is loosely slidable in the guide 12. The back of this valve 13 is

rounded and contacts with the flat face of the disk 14, which is also slidable in the guide 12. A pressure-transmitting member 15, pointed on both ends, has one end slidable in the guide 12 and touching the back surface of the disk 14. The other end of the member 15 contacts the arm 16 of the bell crank 17. The bell crank 17 is pivoted in a bracket 18 which is removably secured in a lug 19 which is integral with the wall of the pressure chamber 3. A valve-closing spring 16^a is seated in the wall of the pressure chamber 3 and presses the arm 16 of the bell crank 17 against the member 15, and consequently tends to hold the valve 13 against its seat 11. The arm 20 of the bell crank is slotted at the end, and the pin 21 of the member 22 is engaged in the slot. The member 22 is commonly called the diaphragm nut, and its stem passes through a hole in the center of the diaphragm 5, and screws into the diaphragm plate 23. A compression spring 24 seats in a circular groove in the diaphragm plate 23 and carries a spring cup 25 at its free end. The spring cup 25 has the tension spring 26 mounted therein, and the free end of the spring 26 is engaged by the point of the adjusting screw 27. The adjusting screw threads through the end of the bell housing 6 and is operated by the handle 28.

The pressure indicator 29 comprises the high-pressure unit 30 and the low pressure unit 31.

The mechanism 29 is mounted and assembled on the dial plate 32, and a high-pressure connecting tube 33 and a low-pressure connecting tube 34 are secured to the indicator mechanism. When the dial plate is assembled in the compartment 4, the tubes 33 and 34 are passed through holes in the partition 2, and then the dial plate 32 is fastened in place by means of screws. This is done before the mechanism in the pressure chamber 3 is assembled in place. The high-pressure tube 34 simply goes through the partition 2. The ends of the tubes can then be sealed in from the open end of the pressure chamber 3.

This provides a very practical way of assembling the pressure indicator into the regulator.

The tube 33 connects the high-pressure indicating mechanism 30 to the inlet; and the tube 34 connects the low-pressure mechanism to the pressure chamber 3. The connection

as shown is not likely to get out of order, and is contained within the housing.

In the operation of pressure regulators, owing to the very severe and exacting duty which a regulator has to perform, it is very frequently necessary to take out the regulator parts in the pressure chamber for cleaning and repairing. Any improvement which improves the accessibility of these parts is quite important to the operator.

When the regulator is to be attached to the storage tank, the adjusting screw 27 is loosened or turned outwardly from the bell housing 6. This relieves the diaphragm 5 from the pressure of the springs 24 and 26. When a connection is made the gas under high pressure is admitted to the inlet passage 7. This pressure is thereby connected to the high-pressure indicator 30 and also flows into the pressure chamber 3 by raising the valve 13 against the tension of the spring 16^a, and the gas flows in through the apertures 9^a in the walls of the guide portion 12 and into the chamber 3. As the pressure is built up in the chamber 3, the diaphragm is flexed outwardly, and because of its connection with the valve 13, it will cause the valve to close. The point at which the pressure on the large area of the diaphragm will cause the valve to be closed against the small area of the inlet is regulated by the spring adjustment on the outer surface of the diaphragm. As the diaphragm is loaded, its power to close the valve is reduced, and consequently higher pressures are maintained in the regulator chamber 3.

When the adjusting screw 27 is first adjusted inward it extends the tension spring 26, and the pressure of the spring 26 is carried through the spring 24 to the diaphragm. As the screw 27 is turned further in, the lengthening of the tension spring 26 is stopped by the bottom of the spring cup 25, and pressure is transmitted from the diaphragm 5 through the heavier compression spring 24. This provides a dual range of adjustments for the regulator.

Having thus described my invention, I claim:

1. In a pressure regulator, the combination of a housing having a transverse partition forming two chambers within the housing, one of said chambers constituting the pressure chamber and having a passage leading into it, and regulator pressure-indicating mechanism mounted in the other chamber and having a tube connection leading through the partition to the inlet passage and a tube connection leading through the partition to the pressure chamber.

2. In a pressure regulator, the combination of a housing having a transverse partition dividing it into a pressure chamber and a compartment, a dial plate removably secured in the compartment, indicating

mechanism mounted on the plate, and connecting tubes secured in the indicating mechanism and adapted to be passed through the partition and sealed from the open end of the pressure chamber.

3. In a pressure regulator, the combination of a housing having transverse partition dividing it into a pressure chamber and a compartment, a diaphragm secured over the open end of the pressure chamber, an inlet nozzle removably secured in the inlet passage in the side wall of the pressure chamber and extending parallel with the diaphragm, a bell crank pivotally mounted in the side wall of the chamber and having an arm parallel to and in pivotal connection with the diaphragm and an arm extending in front of the inlet nozzle, a valve for the nozzle slidably mounted therein, a disk slidable in the nozzle and in point contact with the valve, a member slidable in the nozzle and in point contact with the disk and the second-mentioned bell-crank-arm, and a spring seated in the side wall of the chamber and pressing the second bell-crank arm against the slidable member.

4. In a pressure regulator, the combination of a housing having a transverse partition dividing it into a pressure chamber and a compartment, a diaphragm covering the open end of the chamber, a bell housing clamping the diaphragm in place and removably secured to the main housing, an inlet nozzle removably secured in the inlet passage in the side wall of the pressure chamber and extending parallel with the diaphragm, a bell crank pivotally mounted in the side wall of the chamber and having an arm parallel to and in pivotal connection with the diaphragm and an arm extending in front of the inlet nozzle, a valve for the nozzle slidably mounted therein, a disk slid able in the nozzle and in point contact with the valve, a member slid able in the nozzle and in point contact with the disk and the second-mentioned bell crank arm, a spring seated in the side wall of the chamber and pressing the second bell-crank arm against the slid able member, a compression spring contained in the bell housing and mounted on the inner surface of the diaphragm, a spring cup carried on the outer end of the compression spring, a tension spring mounted in the spring cup, and an adjusting screw threaded through the bell housing and engaging the end of the compression spring.

5. In a pressure regulator, the combination and organization, substantially as described, of a housing having a transverse partition dividing it into a pressure chamber and a compartment, a diaphragm covering the open end of the pressure chamber, a bell housing removably secured to the first mentioned housing and clamping the diaphragm in place, an inlet nozzle removably

secured in the inlet passage in the side wall of the pressure chamber and extending parallel with the diaphragm, a bell crank pivotally mounted in the side wall of the chamber, the first arm of the bell crank being in pivotal engagement with the diaphragm, and the second arm of the bell crank extending in front of the inlet nozzle, a valve for the nozzle and slidably mounted therein, a disk slidable in the nozzle and in point contact with the valve, a member slidable in the nozzle and in point contact with the disk and also in point contact with the second mentioned arm of the bell crank, a spring mounted in the side wall of the chamber and pressing the second mentioned bell crank arm against the slidable member, a dial removably secured in the compartment, indicator mechanism mounted on the dial, and two connecting tubes secured in the indicator mechanism, one of the tubes making a connection to the inlet passage and the other tube making a connection to the pressure chamber.

6. In combination in a pressure regulator, a housing, a transverse partition in the

housing forming a compartment and a chamber which has an outlet and an inlet, pressure regulating means operated by pressures within the chamber, and means within the compartment for indicating both the pressure at the inlet and the pressure within the chamber.

7. In combination in a pressure regulator, a housing, a transverse partition in the housing forming a compartment and a chamber having an inlet, a dial indicator mounted in the compartment and adapted to show both the pressure at the inlet and the pressure in the chamber.

8. In a pressure regulator, a housing, pressure regulating means contained within the housing and having an inlet and an outlet, and pressure indicating means comprising a high pressure unit having an operative connection to the inlet and a low pressure unit having an operative connection with the outlet, said indicating means with the connections being contained entirely within the housing.

JOHN B. BURDETT.
